US00D728573S

(12) **United States Design Patent**
Deng(10) **Patent No.:** **US D728,573 S**
(45) **Date of Patent:** **** May 5, 2015**(54) **COMPUTER INPUT DEVICE**

(71) Applicant: **Jianbo Deng**, Vancouver (CA)
 (72) Inventor: **Jianbo Deng**, Vancouver (CA)
 (**) Term: **14 Years**
 (21) Appl. No.: **29/467,516**
 (22) Filed: **Sep. 20, 2013**
 (51) LOC (10) Cl. **14-02**
 (52) U.S. Cl.
 USPC **D14/409**

Primary Examiner — Deanna L Pratt**CLAIM**

The ornamental design for a computer input device, as shown.

DESCRIPTION

FIG. 1 is a perspective view of the computer input device embodying the new design;

FIG. 2 is a front elevational view thereof;

FIG. 3 is a back elevational view thereof;

FIG. 4 is a top plan view thereof;

FIG. 5 is a bottom plan view thereof;

FIG. 6 is a first side elevational view thereof; and,

FIG. 7 is the other side elevational view thereof.

The broken lines are for environmental subject matter only and form no part of the claimed design.
